US00D616759S

(12) **United States Design Patent**
Toh

(10) **Patent No.:** **US D616,759 S**
(45) **Date of Patent:** **** *Jun. 1, 2010**

(54) **CONTAINER**(75) Inventor: **Kiat Cheong Toh**, Forest Hills, NY (US)(73) Assignee: **Colgate-Palmolive Company**, New York, NY (US)(**) Term: **14 Years**(21) Appl. No.: **29/334,433**(22) Filed: **Mar. 26, 2009****Related U.S. Application Data**

(63) Continuation-in-part of application No. 29/320,254, filed on Jun. 24, 2008.

(51) **LOC (9) Cl.** ..... **09-01**(52) **U.S. Cl.** ..... **D9/563**; D9/564; D9/565; D9/571; D9/574(58) **Field of Classification Search** D9/516, D9/529-530, 537-543, 549, 550-552, 558, D9/563-565, 571, 574-575, 682-694; 215/382-384

FOREIGN PATENT DOCUMENTS

EM ECD 000369459-0006 8/2005

(Continued)

Primary Examiner—Carol Rademaker*(74) Attorney, Agent, or Firm*—Amy M. Fernandez(57) **CLAIM**

The ornamental design for a container, as shown and described.

DESCRIPTION

FIG. 1 is a perspective view of a container of my design;

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawing views are included for the purpose of showing environmental structure that forms no part of the claimed design.

1 Claim, 6 Drawing Sheets# US D616,759 S
